UNITED STATES PATENT OFFICE

1,920,865

ATOMIZER OR SPRAYER

Charles H. Jarvis, Battle Creek, Mich., assignor to United Steel & Wire Company, Battle Creek, Mich.

Application October 3, 1932. Serial No. 635,891

2 Claims. (Cl. 299—58)

The main objects of this invention are:

First, to provide an atomizer or sprayer by means of which a liquid such as water may be effectively atomized and discharged in a mist-like spray which is substantially free from particles of water which would fall as drops.

Second, to provide an atomizer or spray apparatus which is well adapted for use in connection with vegetable stands or display racks and for maintaining a mist-like spray which has been found to be highly effective in keeping vegetables and fruits in a desirable condition and reducing the temperature of the surrounding atmosphere.

Third, to provide an apparatus of this character which may be easily adjusted to regulate the quantity of water discharged and the character of the spray.

Fourth, to provide an apparatus having these advantages which may be easily adjusted by persons not skilled as mechanics.

Fifth, to provide an apparatus which maintains an effective spray with a minimum amount of water.

Objects pertaining to details and economies of the invention will definitely appear from the description to follow. The invention is defined in the claims.

A structure which embodies the features of my invention is clearly illustrated in the accompanying drawing, in which:

Fig. 1 is a fragmentary side elevation of my improved spray unit, portions being shown in section and partially broken away.

Fig. 2 is an enlarged fragmentary vertical section through the nozzle assembly or unit, the valve being shown in full lines.

Fig. 3 is a horizontal section on line 3—3 of Fig. 1.

Fig. 4 is a horizontal section on line 4—4 of Fig. 1.

Fig. 5 is a reduced fragmentary perspective view of the base of the unit.

In the embodiment illustrated in the accompanying drawing I provide an inverted channel-like base 1 which is mounted on a supporting bracket or hanger 2 having laterally projecting flanges 3 and a central opening 4 adapted to receive the casing 5. The pipe coupling 50 having lateral ears 6 is mounted on the base 1 and receives the vertical supply pipe 7 which constitutes a supporting standard. The coupling 50 is adapted to be connected to a suitable source of water supply.

On the upper end of the pipe 7 is a coupling

head 8 having a cylindrical enlarged portion 10 embraced by and constituting a support for the casing 5, the casing enclosing this coupling head. The head is provided with an upwardly facing central socket 11 having an outlet or drain passage 12 discharging within the casing 5 which constitutes a drain conduit. The tubular support 13 is threaded into the socket 11 and is provided with a longitudinal drain slot 14 at its upper end.

An atomizing disk 15 is seated upon the upper end of the drain pipe and has a depending central stem 16 which is recessed within the pipe for positioning and retaining this disk. The sleeve-like combined drain cup and baffle member 17 is threaded upon the support 13 for substantial longitudinal adjustment thereon, the upper or cup-like portion 18 of this member surrounding the atomizing disk in spaced concentric relation thereto. This combined baffle and drain member collects the unatomized water particles and the larger particles, according to its adjustment relative to the impact or atomizing disk, delivering them to the drain pipe through the passages and openings described. By adjusting this member 17 relative to the impact or atomizing disk the character of the spray is controlled. In its extreme upper position only the very finely divided or atomized spray is delivered from the top of the baffle member.

The head 10 in the embodiment illustrated is provided with a pair of upwardly facing sockets 19 and 20, the socket 19 being connected to the supply pipe by a passage 21. Bowed arms 22 and 23 are mounted in these sockets to provide a yoke-like support for the T-shaped body member 24 of the spray nozzle, the arm 22 constituting a water supply conduit. The body member 24 has a cylindrical externally threaded portion 25 receiving the packing gland 26.

A valve member 27 having a stepped bore is removably arranged within this tubular or cylindrical portion 25 of the nozzle body member and has an outwardly extending flange 28 at its outer end which engages the end of the body member when it is forced into position by the packing ring 29 disposed within the gland. The outer and larger portion 30 of the bore of this valve member is internally threaded to receive the externally threaded tubular nozzle member 31.

I provide a needle valve 32 having a stem 33, the upper end of which is frictionally mounted in the reduced bore 34 at the inner end of the valve member, the lower end of which is pro-

vided with an enlargement or flange 35 having a groove 36 therein.

At its inner end the valve member has a passage 37 communicating with the interior of the body member.

The nozzle 38 extends through the opening 39 in the packing gland and is embraced by the packing. This nozzle has a bore 40 constituting a centering bearing or support for the needle valve head 35. At the outer end of its bore 40 the nozzle member has a transverse partition 41 with a central port 42 with which the needle valve 32 coacts. Below this partition the nozzle member has an enlarged chamber 34 terminating in a flared mouth 44 so that the jet is projected from the nozzle without contacting with any part and is effectively protected. The jet may be varied by adjusting the nozzle to open or close the needle valve.

The valve is effectively held in central or concentric relation relative to the walls of the nozzle port so that a perfect stream or jet is discharged and one that is properly directed to strike centrally of the atomizing disk. As stated, by adjusting the member 17 the character of the spray is under effective control, that is, the nozzle may be accurately adjusted to control the amount of water delivered by the needle valve to the disk 15, and the member 17 may be adjusted to control the amount and character of the spray discharged from the disk 15. As a matter of fact, the spray may be so finely atomized as to constitute a fog-like mist which forms and maintains a blanket of cool moist air above the vegetables or fruits when the device is used in that relation, and it is found to very materially reduce the temperature within a substantial area. It is also found that equipment having my improvements embodied therein is highly effective in keeping vegetables and similar green products displayed in stores in a fresh desirable condition.

The apparatus has the very material advantage of effectively maintaining this condition with a minimum of water, so the structure is very economical to operate from that standpoint.

I have embodied my invention in a structure

which has been found very satisfactory in use. I have not attempted to show other adaptations of which my invention is capable as it is believed this disclosure will enable the adaptation thereof by persons skilled in the art.

Having thus described my invention what I claim as new and desire to secure by Letters Patent is:

1. In an atomizer, the combination of a supply pipe, a coupling head on the upper end of said supply pipe having a central threaded socket and a drain passage leading from said socket to the side of said head, said head having a pair of arm sockets, one of said arm sockets being connected to said supply pipe, a casing surrounding said supply pipe and head, a support mounted in said threaded socket and supplying a drain passage, an atomizer disk mounted in said support, a combined drain cup and baffle threaded upon said support for adjustment thereon relative to said atomizing disk, bowed arms mounted in said arm sockets, one of said arms constituting a water delivery pipe, a coupling connecting said arms, and a nozzle mounted on said coupling to discharge a jet of water upon said disk.

2. A vaporizing device comprising a water supply pipe constituting a standard, a head mounted upon said supply pipe, a yoke-like nozzle support mounted on said head, one of the arms of said support constituting a conduit, said head having a passage connecting said conduit to said supply pipe, a downwardly directed nozzle mounted on said nozzle support, a tubular atomizing disk support mounted centrally on said head in alignment with said nozzle, a circular atomizing disk mounted on said support in alignment with said nozzle, a combined drain cup and baffle member threaded upon said disk support for adjustment relative to said atomizing disk, said disk support having a drain opening therein, said head member having a drain passage communicating with said drain opening, and a tubular casing enclosing said supply pipe and head member in supporting engagement with the latter.
